United States Patent

Des. 234,605
Patented Mar. 25, 1975

234,605

PORTABLE RADIO TELEPHONE

Kenneth W. Larson, Elmhurst, Ill., assignor to
Motorola, Inc., Chicago, Ill.

Filed May 31, 1973, Ser. No. 365,772

Term of patent 14 years

Int. Cl. D14—03

U.S. Cl. D26—14 K

FIG. 6

FIG. 5

FIG. 1 is a view in perspective of a radio telephone showing my new design;

FIG. 2 is a view of the right side elevation thereof;

FIG. 3 is a view in rear elevation thereof;

FIG. 4 is a view in bottom plan thereof;

FIG. 5 is a view in front elevation thereof; and

FIG. 6 is a view in top plan thereof.

The left elevation view not shown is substantially the mirror image of the right side elevation shown in FIG. 2.

I claim:

The ornamental design for a portable radio telephone, as shown and described.
